BUILDING SHELL

Lawrence A. Samuelson, Houston, Tex., assignor of
fractional part interest to Michael D. Reifel, Houston,
Tex.

Filed July 30, 1969, Ser. No. 18,463

Term of patent 14 years

Int. Cl. D25—04

U.S. Cl. D13—1

FIG. 1

FIG. 2

FIG. 3

FIG. 4

FIG. 6

FIG. 5

FIG. 1 is a front perspective view of a building shell embodying the design which is characterized by an assembly of modular elements having the shape of hyperbolic paraboloids. The foundation, windows and door are shown by broken lines for illustrative purposes only.

FIG. 2 is a front elevation of the building shell.

FIG. 3 is a top plan view of the building shell.

FIG. 4 is a side elevation of the building shell.

FIG. 5 is a sectional view taken along lines 5—5 in FIG. 4.

FIG. 6 is a sectional view taken along lines 6—6 in FIG. 4.

I claim:

The ornamental design for a building shell, substantially as shown and described.
